FORM CLAMP MECHANISM FOR PRESSES

George M. Pfaller, Pittsburgh, and August A. Saul,
Ross Township, Allegheny County, Pa.

Application September 6, 1952, Serial No. 308,276

5 Claims. (Cl. 101—250)

This invention relates to form clamp mechanism for presses. It relates more particularly to mechanism for insuring against operation of a press when the form clamps are in inoperative position.

The invention relates generally to presses to which a form is adapted to be applied on a movable bed. The invention is applicable to printing and other presses, such, for example, as cutting and creasing presses. For purposes of explanation and illustration the invention will be described as embodied in form clamp mechanism for a press of the flat bed and cylinder type.

In a press of the flat bed and cylinder type the press bed oscillates in a plane and sheets being operated upon are successively brought into contact with a form clamped to the bed when the bed moves in one direction by being pressed against the form by a so-called impression cylinder. Upon the return movement of the bed the impression cylinder is raised so as not to engage the form.

The form is fastened to the bed by form clamps. In one well known form of structure the form may bear endwise and laterally against an end member and two side members on the bed, the bed having an open end through which the form may be introduced and removed. Form clamps are carried by the bed at the open end thereof which when the form has been introduced are moved to form clamping position and complete the retention of the form on the bed.

It is customary to make up the form in a chase at a location remote from the press and to bring the made up form in the chase to the press and place it on the press bed and clamp it in place by rendering operative the form clamps at the end of the bed. Occasionally the pressman may forget to render operative the form clamps. When that happens the form may fly off of the bed at the end of the return stroke of the bed since the movement of the bed is quickly reversed and if there is nothing to hold the form in place its inertia is likely to cause it to continue moving while the bed reverses. This causes damage and delay.

Our form clamp mechanism insures against the damage and delay incident to a form flying off of a press bed in that we insure against the possibility that the press may be operated unless the form clamps have first been rendered operative to clamp the form in place on the bed.

We provide, in a press having a movable bed adapted to carry a form and having form clamping means connected with the bed and movable between operative form clamping position and inoperative position and means for moving the bed, connections between the form clamping means and the means for moving the bed rendering inoperative the means for moving the bed when the form clamping means are in inoperative position. We preferably provide control means for the means for moving the bed and connections between the form clamping means and the control means mounted to actuate the control means to render inoperative the means for moving the bed when the form clamping means are in inoperative position. We preferably dispose the control means alongside (laterally of, above or below) the path of movement of the bed and provide actuating means for actuating the control means, the actuating means being carried by the bed, together with connections between the form clamping means and the actuating means moving the actuating means to actuate the control means to render inoperative the means for moving the bed when the form clamping means are in inoperative position.

2

We also provide, in a press having a bed adapted to carry a form and a plurality of form clamps connected with the bed and each movable between operative form clamping position and inoperative position, connections between the form clamps insuring synchronous operation thereof so that when one of the form clamps is moved to one of said positions the remainder thereof will be similarly moved. The form clamps are preferably pivotally connected with the bed and each turnable between operative form clamping position and inoperative position and the means insuring synchronous operation of the form clamps are preferably pivotally connected with the respective form clamps. By "operative form clamping position" is meant position in alignment with the form in the direction of movement of the bed. In one conventional form of press four form clamps are pivotally mounted at the end of the bed, although the number of form clamps may be varied as desired. Each clamp may be pivotally mounted on a screw threaded into the end of the bed so that after the clamp is turned to operative form clamping position about the axis of the screw the screw may be turned so that its head moves toward the end of the bed until it engages the clamp and presses it against the form.

We further provide, in a press having a movable bed adapted to carry a form and having form clamping means connected with the bed and movable between operative form clamping position and inoperative position and means for moving the bed, means connected with the form clamping means shiftable transversely of the direction of movement of the bed upon movement of the form clamping means between operative and inoperative positions and means positioned in the path of the last mentioned means and operable thereby upon movement of the form clamping means to inoperative position to render inoperative the means for moving the bed. We preferably provide spring means maintaining the shiftable means and the last mentioned means in contact in all positions of the shiftable means. The shiftable means may partake of its shifting movement laterally of the bed or in another direction transversely of the direction of movement of the bed.

In a preferred form of structure we provide means carried by the bed movable between a first position rendering operative the means for moving the bed and a second position rendering inoperative the means for moving the bed together with means connected with the form clamping means shiftable transversely of the direction of movement of the bed upon movement of the form clamping means between operative and inoperative positions and connected with the means carried by the bed moving the same to the second position thereof when the form clamping means are moved to inoperative position.

When control means for the means for moving the bed are disposed alongside the path of movement of the bed and actuating means are provided as above mentioned for actuating the control means the actuating means are preferably carried by the bed, desirably at a side thereof, movable between a first position in which the means for moving the bed is operative and a second position actuating the control means to render inoperative the means for moving the bed, and means are preferably provided as above described connected with the form clamping means shiftable transversely of the direction of movement of the bed upon movement of the form clamping means between operative and inoperative positions and connected with the actuating means moving the same to the second position thereof when the form clamping means are moved to inoperative position.

Desirably the means for moving the bed are electrically operated, in which case the control means may comprise a switch disposed alongside the path of movement of the

bed rendering the electrically operated means for moving the bed operative in a first position of the switch and inoperative in a second position of the switch. The actuating means may comprise an actuating member pivoted at one end to the bed and extending generally longitudinally of the bed turnable about its pivotal connection with the bed between a first position in which the switch is in its first position and a second position actuating the switch to its second position together with means pivotally connected with the actuating member at a point remote from its pivotal connection with the bed and also connected with the form clamping means shiftable transversely of the direction of movement of the bed upon movement of the form clamping means between operative and inoperative positions moving the actuating member to its second position when the form clamping means are moved to inoperative position.

Other details, objects and advantages of the invention will become apparent as the following description of a present preferred embodiment thereof proceeds.

In the accompanying drawings we have shown a present preferred embodiment of the invention in which

Figure 1 is a diagrammatic fragmentary end view of a flat bed and cylinder press showing our form clamp mechanism; and

Figure 2 is a diagrammatic fragmentary plan view of a portion of the structure shown in Figure 1.

Referring now more particularly to the drawings, there is shown a flat bed and cylinder press including a stationary frame designated generally by reference numeral 2 in which is mounted in conventional manner for rectilinear oscillation in a horizontal plane a bed 3. The bed has at its sides longitudinally extending bearers one of which is shown at 4, one of whose functions is to laterally confine the form which is laid upon the bed. There are two such bearers, one at each longitudinally extending edge of the bed. The bed also has a transverse member 4a at the end thereof opposite the end viewed in Figure 1. The form is laid upon the bed 3 between the bearers and against the transverse member 4a above mentioned. The form is adapted to be clamped in place by four form clamps 5 only two of which are shown in the drawings. Each of the form clamps 5 is pivoted to the end of the bed by a screw 6 and is adapted to be turned about the axis of its screw between a generally upright operative position as shown in Figure 1, in which position it clamps the form in place on the bed when the screw is tightened, and an inoperative position turned in the counterclockwise direction from the operative position viewing Figure 1 through an angle of approximately 90°. A stop pin 7 is provided adjacent each clamp 5 limiting the turning movement of the clamp in the clockwise direction viewing Figure 1 to determine its operative position.

We provide a bar 8 extending transversely of the direction of movement of the bed and specifically, in the form shown, laterally of the bed, having four downwardly extending lugs 9 having the same transverse spacing as the clamps 5 and each lug 9 being pivotally connected with one of the clamps 5 by a pivot pin 10. Only two of the four lugs 9 are shown in the drawings. Each of the pivot pins 10 is disposed directly above the corresponding screw 6 when the corresponding clamp 5 is in operative position. Thus the bar 8 connects together all of the clamps 5 so that when any one of the clamps 5 is moved to a particular position the remainder of the clamps will be similarly moved. The provision of the bar 8 not only has the advantage of insuring synchronous movement of all of the clamps whereby in turn to insure that when one of the clamps is in operative position all of the clamps will be in operative position but also has the further advantage that by operation of one clamp, or, indeed, by operation of the bar 8, all of the clamps may be simultaneously turned, thus saving the time required to individually turn the respective clamps. The left hand lug 9 viewing Figure 1

has an extension 11 projecting toward the left and having its left-hand end face shaped to provide a lower substantially vertical portion 12 and an upper concavely curved portion 13 as shown in Figure 1.

Projecting horizontally from the end of the bed adjacent the left-hand side thereof viewing Figure 1 are two pins 14 which serve as supports for a slide 15 lying against the end face of the bed and having an elongated slot 16 extending transversely of the bed through which the pins 14 project. A washer 17 and a cotter pin 18 may be applied to either or both of the pins 14 to maintain the slide 15 in place. Thus the pins 14 support the slide 15 for rectilinear sliding movement transversely of the bed.

Carried by and projecting horizontally from the slide 15 is a pin 19 against which the left-hand face of the left-hand lug 9 is adapted to bear as shown in Figure 1. Carried by the slide 15 and projecting downwardly therefrom is a pin 20 to which is connected one end of a tension coil spring 21 the other end of which is connected to a pin 22 carried by the bed. The coil spring 21 maintains the pin 19 always in engagement with the left-hand face of the left-hand lug 9.

Pivoted to the bed 3 at a portion 3a at a side thereof by a vertical pivot 23 is a bar 24 shown as being curved so that it is somewhat convex at its outer face as shown in Figure 2. The slide 15 has a projection 25 which extends toward the left viewing Figure 1, and the end of the bar 24 opposite the end which is pivoted to the bed at 23 overlies the extension 25 and is pivoted thereto by a pivot pin 26. The bed is operated in conventional fashion by an electric motor. In the motor circuit is a switch 27 carried by the frame 2 and having a downwardly projecting switch operating shaft 28 carrying an arm 29 which in turn carries a roller 30 positioned to be engaged by the bar 24. The bar 24 has two positions shown in Figure 2, one in full lines and the other in chain lines. When the bar 24 is in the full line position viewing Figure 2 the switch 27 is closed and the bed operating motor is operative. When the bar 24 is in the chain line position of Figure 2, i. e., positioned generally outwardly relatively to the bed, the switch 27 is operated through the engagement of the bar 24 with the roller 30 to open the switch and render inoperative the bed driving motor.

When the clamps 5 are in operative position as shown in Figure 1 with each clamp disposed upright with its right-hand side face against the corresponding stop pin 7 the bar 8 is in its extreme right-hand position viewing that figure. When the bar 8 is in that position the pin 19 carried by the slide 15 engages the portion 12 of the left-hand face of the left-hand lug 9 as shown, the tension coil spring 21 maintaining the pin 19 always in contact with the left-hand face of the left-hand lug 9 as above explained. Thus when the bar 8 is in its extreme right-hand position viewing Figure 1 the slide 15 is likewise in its extreme right-hand position and the bar 24 is in its position first referred to above in which it is relatively retracted from the switch 27 and the switch is closed permitting normal operation of the press.

When, however, the clamps 5 are moved to inoperative position, i. e., turned through an angle of about 90° in the counterclockwise direction viewing Figure 1 from the positions in which they are shown in that figure, the bar 8 moves toward the left and downwardly, camming the slide 15 toward the left by engagement of the left-hand face of the left-hand lug 9 with the pin 19 which when the bar 8 is in its extreme leftward position is in engagement with the upper part of the portion 13 at the left-hand face of the left-hand lug 9. But movement of the slide 15 toward the left viewing Figure 1 moves the bar 24 from the full line position to the chain line position of Figure 2. The result of such movement of the bar is to open the switch 27 and render the bed operating motor inoperative. Thus our form clamp mechanism insures against damage and delay which may result by opera-

tion of the press with the form clamps in inoperative position. It will, of course, be understood that the switch 27, being mounted on the stationary frame, remains in a fixed location as the bed oscillates during operation of the press. When the bar 24 is in its outer position as shown in chain lines in Figure 2 so as to open the switch 27 it will open the switch in any relative position of the bed relatively to the switch, although the bar may be so designed as to cooperate with the switch only when the bed is near the end of its stroke in the direction toward the end of the bed viewed in Figure 1 since the only time when the clamps 5 will be rendered inoperative is when it is desired to remove or apply the form which can be done only when the bed is completely removed from beneath the impression cylinder.

While we have shown and described a present preferred embodiment of the invention it is to be distinctly understood that the invention is not limited thereto but may be otherwise variously embodied within the scope of the following claims.

We claim:

1. In a press having a movable bed adapted to carry a form and having a plurality of form clamps connected with the bed and each mounted for swinging movement between a position in alignment with the form and a position out of alignment with the form and electrically operated means for moving the bed, a switch disposed alongside the path of movement of the bed rendering the electrically operated means for moving the bed operative in a first position of the switch and inoperative in a second position of the switch, actuating means for actuating the switch carried by the bed movable between a first position in which the switch is in its first position and a second position actuating the switch to its second position and means connected with the form clamps insuring synchronous operation thereof so that when one of the form clamps is swung to one of said positions the remainder thereof will be similarly swung, the last mentioned means being shiftable transversely of the direction of movement of the bed upon swinging of the form clamps between said positions and operatively connected with the actuating means moving the same to the second position thereof when the form clamps are swung to inoperative position.

2. In a press having a rectilinearly oscillatable bed adapted to carry a form and having a plurality of form clamps connected with the bed and each mounted for swinging movement between a position in alignment with the form and electrically operated means for oscillating the bed, a switch disposed alongside the path of oscillation of the bed rendering the electrically operated means for oscillating the bed operative in a first position of the switch and inoperative in a second position of the switch, actuating means for actuating the switch carried by the bed movable between a first position in which the switch is in its first position and a second position actuating the switch to its second position and connecting means connected with the form clamps insuring synchronous operation thereof so that when one of the form clamps is swung to one of said positions the remainder thereof will be similarly swung, the last mentioned means being shiftable transversely of the direction of movement of the bed upon swinging of the form clamps between said positions and operatively connected with the actuating means moving the same to the second position thereof when the form clamps are swung to inoperative position.

3. In a press having a movable bed adapted to carry a form and having a plurality of form clamps connected with the bed and each mounted for swinging movement between a position in alignment with the form and a position out of alignment with the form and electrically operated means for moving the bed, a switch disposed alongside the path of movement of the bed rendering the electrically operated means for moving the bed operative

in a first position of the switch and inoperative in a second position of the switch, an actuating member for actuating the switch pivoted at one end to the bed and turnable about its pivoted connection with the bed between a first position in which the switch is in its first position and a second position actuating the switch to its second position and connecting means connected with the form clamps insuring synchronous operation thereof so that when one of the form clamps is swung to one of said positions the remainder thereof will be similarly swung, the last mentioned means being shiftable transversely of the direction of movement of the bed upon swinging of the form clamps between said positions and operatively connected with the actuating means moving the same to the second position thereof when the form clamps are swung to inoperative position.

4. In a press having a rectilinearly oscillatable bed adapted to carry a form and having a plurality of form clamps connected with the bed and each mounted for swinging movement between a position in alignment with the form and a position out of alignment with the form and electrically operated means for oscillating the bed, a switch disposed alongside the path of oscillation of the bed rendering the electrically operated means for oscillating the bed operative in a first position of the switch and inoperative in a second position of the switch, an elongated actuating member for actuating the switch pivoted at one end to the bed and extending generally longitudinally of the bed and turnable about its pivotal connection with the bed between a first position in which the switch is in its first position and a second position actuating the switch to its second position and connecting means connected with the form clamps insuring synchronous operation thereof so that when one of the form clamps is swung to one of said positions the remainder thereof will be similarly swung, the last mentioned means being shiftable transversely of the direction of movement of the bed upon swinging of the form clamps between said positions and operatively connected with the actuating member moving the same to the second position thereof when the form clamps are swung to inoperative position.

5. In a press having a movable bed adapted to carry a form and having a plurality of form clamps connected with the bed and each mounted for swinging movement between a position in alignment with the form and a position out of alignment with the form and electrically operated means for moving the bed, a switch disposed alongside the path of movement of the bed rendering the electrically operated means for moving the bed operative in a first position of the switch and inoperative in a second position of the switch, actuating means for actuating the switch carried by the bed movable between a first position in which the switch is in its first position and a second position actuating the switch to its second position and connecting means connected with the form clamps insuring synchronous operation thereof so that when one of the form clamps is swung to one of said positions the remainder thereof will be similarly swung, the last mentioned means being shiftable transversely of the direction of movement of the bed upon swinging of the form clamps between said positions and including cam means moving the actuating means to the second position thereof when the form clamps are swung to inoperative position.
